AUTOMATIC PAPER CARRIER

John Q. Sherman, Dayton, Ohio

Application January 2, 1932, Serial No. 584,321

56 Claims. (Cl. 197—133)

This invention relates to typewriting machines, and more particularly to a motor actuated paper supply carrier therefor traveling to and fro in unison with the typewriter carriage, 5 but propelled independently thereof whereby the typewriter mechanism may be relieved of load and strain.

While it is old in this art to provide a reciprocating paper carrier mounted in the rear of a typewriter and actuated to and fro by the movement of the typewriter carriage, in the present instance the paper carrier is provided with propelling means independently of the typewriter by which the carrier is automatically advanced 15 in unison with the movement of the typewriter carriage which acts as a governor restraining and controlling such advance movement. The paper carrier being automatically returned under motive influence carries with it the typewriter carriage preparatory to the next line writing 20 operation. Such motor actuated return movement of the paper carrier and writing machine carriage may be effected by operation of the line spacing device of the writing machine or by operation of a special key or lever and may be automatically arrested when the carrier and typewriter carriage have been returned to a predetermined position.

The object of the invention is to improve the 30 construction as well as the means and mode of operation of paper supply carriers for a writing machine, whereby they will not only be cheapened in construction but will be more efficient in use, automatic in action, uniform in operation and unlikely to get out of repair.

A further object of the invention is to provide a paper supply carrier for a writing machine which is propelled independently of but in unison with the traveling carriage of the writing machine and which will not subject the latter to undue stress or strain.

A further object of the invention is to provide actuating means for a paper supply carrier for a writing machine adapted to impart thereto alternating motion, first in one direction and then in the other.

A further object of the invention is to provide means for automatically returning the writing machine carriage in unison with the return of the 50 paper supply carrier.

A further object of the invention is to provide an automatically traveling carrier for a paper supply having propelling means other than the writing machine with which it is employed. The 55 movement of the carrier under its own motive

power in one direction is controlled by the operation of the writing machine, and upon actuation thereof in reverse direction it transmits return motion to the writing machine carriage.

A further object of the invention is to provide 5 a unitary motor actuated paper supply carrier applicable to different writing machines.

A further object of the invention is to provide means for automatically effecting the return of the paper supply carrier by the operation of the 10 line spacing device of the writing machine.

A further object of the invention is to provide an improved actuator for the paper supply carrier, and means whereby the actuator is intermittently connected with and disconnected from 15 the carrier.

A further object of the invention is to provide improved control means for the motor actuated paper carrier.

With the above primary and other incidental 20 objects in view, as will more fully appear in the specification, the invention consists of the features of construction, the parts and combinations thereof, and the mode of operation, or their equivalents, as hereinafter described and set 25 forth in the claims.

Referring to the accompanying drawings, 30 wherein is shown the preferred but obviously not necessarily the only forms of embodiment of the invention, Fig. 1 is a side elevation of a conventional form of typewriter and traveling supply carrier to which the present invention has been applied. Fig. 2 is a front elevation of the paper supply carrier detached from the writing machine. Fig. 3 is an enlarged end view of the base 35

portion of the paper supply carrier illustrating its mounting and the application thereto of an actuating motor. Fig. 4 is a detail view of the actuator for advancing the paper carrier in unison with the movable writing machine carriage. Fig. 40

Fig. 5 is a detail perspective view of the driving connection for returning the paper carrier and disconnecting the actuator at the limit of its return movement. Fig. 6 is an end elevation, partly in 45

section, of the construction illustrated in Fig. 5. Fig. 7 is a detail perspective view partly diagrammatical of the means for electrically energizing the motor for retraction of the carrier. Fig. 8

is a perspective view illustrating a modification 50 of the construction shown in the preceding figures wherein a single actuating pinion and gear rack are employed for propelling the paper carrier in alternate directions controlled by an electrically operated clutch mechanism. Fig. 9 is a 55 detail sectional view of the driving mechanism

illustrated in Fig. 8. Fig. 10 is a further modification thereof. Fig. 11 is a side elevation of the actuating motor illustrated in Fig. 1 employing frictional power transmission means for retracting the paper carrier. Fig. 12 is a detail perspective view of the interconnection of the motor control means with the line spacing mechanism. Like parts are indicated by similar characters of reference throughout the several views.

Referring to the drawings, 1 is a conventional form of writing machine or typewriter having a traveling carriage 2 in which may be mounted the usual platen roll and provided with the usual line spacing mechanism including the operating lever 3 for advancing the platen roll through a step by step movement at the completion of succeeding lines of writing. The invention is likewise applicable to writing machines of the billing machine type wherein the traveling carriage moves the type relative to a stationary platen. It is to be understood that the invention does not depend upon the particular type or style of writing machine and that the typewriter disclosed in the drawings is employed merely for illustrative purposes.

Mounted in the rear of the writing machine for to and fro travel in unison with the typewriter platen carriage is a paper supply carrier 5 mounted in rearwardly inclined position upon a guide track 6 supported upon standards 7 arising from a base 8. The carrier 5 is provided with anti-friction bearings 9 between its base and the guide track 6. It is further provided with adjustable arms 10 extending on opposite sides of the reciprocating carriage 2 of the typewriter, whereby the carrier and carriage are operatively interconnected for unison travel. Such connection permits free vertical movement of a platen carriage as is ordinarily necessary with such carriage for writing capital letters and symbols when used but maintains the relative relation of the carriage and paper carrier during their to and fro travel.

Mounted upon a suitable dependent bracket 12 secured to the supporting track 6, as is illustrated more particularly in Fig. 3, is a spring propeller comprising a gear pinion 13 actuated by a convolute spring 14 and having operative driving engagement with a gear rack 15 carried upon the reciprocating paper supply carrier 5. The propeller pinion 13 is loosely journaled upon a supporting stud 16 fixedly secured to the bracket 12 and slotted at 17 to receive one end of the convolute actuating spring 14, the opposite end of which is secured to the propeller pinion. The spring 14 is enclosed within a housing comprising a cap portion 18 having telescopic engagement with a circular flange or enclosure 19 upon the propeller pinion and surrounding the actuating spring 14.

The actuating spring 14 is tensioned or wound by the retractive movement of the paper supply carrier which, operating through the gear rack and pinion, imposes upon the spring sufficient tension to drive the paper supply carrier through its range of movement in unison with the travel of the writing machine carriage. The spring actuator means, however, propels the paper carrier independently of the driving or power influence of the writing machine. The writing machine carriage operates as a governor to control the advance movement of the paper carrier under influence of the spring actuator limiting it to a step by step movement determined in the usual manner by the operation of the writing machine

keys. Thus while the traveling paper carrier moves in unison with the writing machine carriage, the latter is subjected to no strain or load, and instead of affording the propelling influence as is usual in such combination, the writing machine carriage in the present instance affords a retarding influence, restraining the advance of the paper carrier and limiting its movement under influence of the spring motive means to a rate of travel synchronous with that of the writing machine carriage.

In order to automatically return the traveling paper carriage after each line writing operation, there is provided an electric motor 20 mounted for oscillatory motion in a supporting bracket or standard 21 and operating through a suitable speed reduction mechanism preferably, though not necessarily, of the worm gear type to drive an actuating pinion 22 having operative engagement with a second gear rack 23 also carried upon the base portion of the reciprocating paper carrier 5. The driving pinion 22 is intermittently moved into and out of driving engagement with the rack 23 by the oscillatory adjustment of the actuating motor 20. Such adjustment of the actuating motor together with the closing of the energizing circuit is, as here shown but not necessarily, effected by the operation of the line spacing mechanism controlled by the lever 3.

In the present disclosure there has been shown, merely for illustrative purposes, a conventional type of line spacing mechanism wherein the operating lever 3 mounted upon the traveling carriage 2 is provided with a rock arm 25 connected by a link 26 with a rocker member or bell crank 27 connected by a reciprocating link 28 with an actuating pawl 29 engaging the usual ratchet wheel upon the writing machine platen roll. Such construction has been illustrated in Figs. 1 and 2. In the present construction the rocker member 27 is slidable to and fro upon a splined rock shaft 30 mounted in the frame of the writing machine. Thus the rocker member 27 which, in the ordinary writing machine construction is pivoted directly to the traveling carriage, in the present instance travels to and fro upon the rock shaft 30 as the platen carriage is reciprocated and is operated to rock such splined rock shaft 30 simultaneously with the actuation of the spacing mechanism. That is to say whenever the line spacing lever 3 is manipulated to advance the platen roll, the rocking motion is transmitted to the shaft 30 through the rock arm 25, link 26 and rocker member 27, whatever the lineal position of the traveling carriage may be. Secured upon the splined rock shaft 30 is a rock arm 31 connected by a link 32 with a motor control lever 34 pivoted at 33 to the frame of the writing machine. The rear end of this motor control lever 34 is connected by a loose pivotal or slotted connection 35 with an arm 36 upon the oscillatory motor 20. The oscillation of the motor control lever 34, under influence of the line spacing mechanism to which motion is transmitted through the link 32, turns the actuating motor 20, in its mounting 21, to engage the driving pinion 22 thereof with the gear rack 23 upon the base of the traveling paper carrier. At the same time the forward end of the motor control lever 34 being depressed by the oscillatory motion of such lever closes an electric switch 37 thereby closing the motor energizing circuit 38 through a suitable source of electrical energy and energizing the motor 20 to return the paper carrier. Adjustably secured upon the base of 75

the paper carrier in such position as to engage the hub 39 of the actuating pinion 22 is a cam 40 which, as the paper carrier reaches the limit of its return movement, operates to depress the gear pinion 22 out of driving engagement with the rack 23 by turning the motor 20 about its pivotal connection with its mounting 21 thus arresting the return movement of the paper carrier. This camming action of the cam 40 upon the hub 39 of the gear pinion 22 at the same time operates through the arm 36 to return the motor control lever 34 to its normal position thereby permitting the switch 31 to open, deenergizing the motor circuit. For economy of manufacture and simplicity of adjustment, the disengaging cam 40 is carried upon a slotted slide block 41 which straddles the gear rack 23 and is adjustably secured thereon by a set screw 42. By adjustment of the cam 40, the range of travel of the paper carrier 5 may be varied.

In Fig. 7 there is shown the line spacing lever of a popular type of writing machine with which is associated an electric switch 43 directly engaged by the line spacing lever and operating to close the motor circuit.

In the construction heretofore described, there are employed two actuators or propellers, one of which comprises the spring actuated driving gear 13 propelling the paper carrier in one direction and the other comprising the motor actuated gear pinion 22 propelling the paper carrier in reverse direction. The retracting motor has sufficient power to overcome and rewind the actuating spring 14 of the primary propelling pinion 13, whereby the latter is retensioned at each retractive operation preparatory to the next line writing operation. Not only does the motor 20 possess sufficient power to overcome and rewind the primary actuating spring, but it also serves to automatically return in unison with the paper carriage the traveling writing machine carriage with which the paper supply carrier is operatively connected for unison travel. Thus while the writing machine carriage controls the paper carrier during its operative movement in one direction, the paper carrier in turn propels the carriage during its retractive movement. Although the actuator for retracting the traveling paper carrier is preferably controlled by the operation of the normal line spacing mechanism of the writing machine as has been heretofore described, it may, if desired, be controlled by a special key and to this end the forward extremity of the motor control lever 34 has been provided with a head 34a by which the lever may be manually depressed to tilt the motor 20 to effect operative engagement of the actuating pinion 22 and gear rack 23 and at the same time close the motor circuit switch 31.

In lieu of the gear drive mechanism for transmitting motion to the reciprocating paper carrier, the latter may be provided with a friction bar 44, as illustrated in Fig. 11, with which engages a friction wheel 45 in lieu of the gear pinion 22. The traction bar 44 has been shown provided with a V shaped groove and the periphery of the friction driving wheel 45 is similarly shaped to afford the necessary driving engagement.

While the construction as heretofore described includes separate actuators for propelling the paper carrier in alternate direction, there is shown in Figs. 8 and 9 an alternative construction wherein the same propeller pinion is employed for alternate driving operation. In such construction the primary driving pinion 13, hav-

ing operative engagement with the gear rack 12 upon the carrier, is mounted upon a rotary shaft 46 mounted in suitable bearings 47 on the under side of the supporting track upon which the paper carrier travels. The propeller pinion 13 is provided with the actuating spring enclosed within the housing 18 as before described, and operates in the same manner as heretofore described to impel the paper carrier during the normal writing operation. The pinion shaft 46 carries a clutch member 48 engageable with a clutch element 49 carried by a motor driven shaft 50 actuated from the electric motor 20 through a suitable safety friction drive coupling 51. This friction drive coupling 51 comprises alternating friction discs which serve to transmit motion from the actuating motor to the shaft 50 and are adapted to slip in the event of undue resistance to rotation of the shaft. The tension of such friction coupling device may be varied by adjustment of the nut 52 upon the extremity of the shaft 50 by which the tension of the spring 53 may be varied, thereby varying the pressure of the discs comprising the coupling element. Such friction coupling device is old in this art and forms no part, per se, of the present invention and is included merely as a safety feature. Any suitable means may be employed for shifting the clutch member 48 into and out of engagement with the coating member 49. Such shifting movement may be effected by the operation of the line spacing mechanism as before described, or by operation of a special key. However as an alternative construction there is illustrative in Fig. 8 an electromagnetic means comprising a solenoid 54, the reciprocating core 55 of which is connected with a shift lever 56 engaging the clutch member 48 to shift the same upon the shaft 44 into and out of driving engagement with the clutch element 49. The solenoid 54 may be controlled by the switch 34, illustrated in Fig. 1, or by the switch as shown in Fig. 7 wherein the electric switch controlled by the spacing lever is shown diagrammatically connected with the actuating motor 20 and with the clutch operating solenoid 54. So long as the clutch elements 48 and 49 are disconnected the propeller pinion 13 is operated under the influence of a spring to actuate the paper carrier in one direction. However, by interconnecting the clutch elements 48 and 49 either by mechanical means or by the electrically operated mechanism, shown in Fig. 8, the propeller pinion 13 will be driven in reverse direction and against the tension of its normal actuating spring within the spring housing to retract the paper carrier and, at the same time, rewind the primary actuating spring. Obviously the traveling typewriter carriage 2 of the writing machine will be retracted in unison with the retraction of the paper carrier with which it is operatively connected by the spaced arms.

In Fig. 10 there is shown a further modification wherein the clutch members are actuated by direct electrical influence. In this construction one clutch element 49' is fixedly connected upon the shaft 44 while the movable clutch element 48' is slidably adjustable thereon and is operatively connected with a head or collar 57 upon the shaft 50 by means of studs or pins 58. The movable clutch element 48' comprises the reciprocating core of a solenoid or electromagnetic coil 59. Whenever such solenoid coil is energized by the closing of the electric switch 37, the movable clutch element 48' is retracted 75

against the tension of the interposed spring 60 into driving engagement with the clutch element 49' secured upon the shaft 44 whereupon a direct driving engagement is established from the actuating motor 20 to the propeller pinion 13 which is thereby driven in reverse direction to rewind its actuating spring and to retract the paper carrier and with it the writing machine carriage. The spring 60, shown in Figs. 9 and 10, is interposed between the respective clutch elements 48 and 49 to insure disengagement of these clutch elements upon deenergization of the controlling electrical circuit.

While as heretofore described the electric motor may be interengaged with the carrier for retractive movement thereof by either the actuation of the line spacing lever or by direct manual actuation of the motor control lever 34 which is provided with the head 34a for this purpose, in which case the line spacing occurs at the beginning of the retractive movement, for certain conditions of use it may be quite desirable to effect automatic line spacing operation as the carrier reaches the limit of its return movement. This may be accomplished by the very simple expedient of reversing the position of the rock arm 31 upon the shaft 30 whereby the arm will rock upward coincident with the rocking motion of the shaft incident to the line spacing operation instead of downwardly as shown in Fig. 12. In such event the link 32 connected at its upper end to the arm 31 will be connected at its lower end to the lever 34 by the pivotal screw 32a, Fig. 1. In such arrangement, the motor is engaged with the carrier by manual depression of the control lever 34, the head 34a of which is provided for such purpose. Upon such movement of the lever the line spacing mechanism including the rock shaft 30, the rocker 27, link 28 and pawl 29 with the normal line spacing lever 3 will be operated idly in a reverse direction by the transposed link 32 and reversed rock arm 31. As the carrier reaches the limits of its return movement the cam 40 by its engagement with the hub 39 of the actuator gear rocks the motor out of engaging relation with the carrier thereby returning the control lever 34 and transmitting through the link 32 and reversed rock arm 31 actuating motion to the line spacing devices. Thus the line spacing is automatically accomplished at the completion of the motor actuated retraction of the paper carrier and traveling typewriter carriage.

The stationary mounting of the traveling paper carrier is provided with means for attaching it to a writing machine frame or to a desk in fixed relation therewith, while the traveling carriage of such carrier is provided with means for coupling it to the traveling typewriter carriage for unison to and fro motion. Such unitary construction including the mounting, the motor, reciprocatory carriage and motor control means, and the coupling means connecting the traveling carrier, either with or without the paper holder or compartment may be utilized as an attachable power unit for various mechanisms other than writing machines wherein a reciprocatory member is to be alternated to and fro, and may be used to electrically return the carriage of an ordinary typewriter, even though not used to carry the paper supply therefor.

From the above description it will be apparent that there is thus provided a device of the character described possessing the particular features of advantage before enumerated as desira-

ble, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific features shown, but that the means and construction herein disclosed comprise the preferred form of several modes of putting the invention into effect, and the invention is therefore claimed in any of its forms or modifications within the legitimate and valid scope of the appended claims.

Having thus described my invention, I claim:

1. The combination with a writing machine including a reciprocatory carriage and a traveling paper supply carrier interconnected with the carriage for to and fro motion, of motor actuating means for the traveling paper supply carrier, the movement of the carrier in one direction under influence of the motor actuating means being controlled by the movement of the carriage, and the motor actuated movement of the paper carrier in the opposite direction being transmitted to the carriage which is automatically returned thereby.

2. The combination with a writing machine including a reciprocatory carriage and a traveling paper supply carrier interconnected with the writing machine carriage spring driven in one direction for unison to and fro motion, of motor actuating means for the traveling paper supply carrier actuating the carrier in opposition to the spring driven carriage, the movement of the traveling carrier in one direction being restrained by the writing machine carriage to a unison rate of travel therewith.

3. The combination with a writing machine having a spring driven traveling carriage of a paper supply carrier interconnected with the printing machine carriage for unison to and fro motion, of an electric motor actuating means for the traveling paper supply carrier in opposition to the influence of the spring driven carriage and independently of the writing machine, the movement of the traveling paper carrier in one direction under motor actuating influence being controlled by the operation of the writing machine.

4. The combination with a writing machine including a reciprocatory carriage normally spring driven in one direction and a traveling paper supply carrier interconnected with the carriage for unison to and fro motion, of motor actuating means for the traveling paper supply carrier in opposition to the influence of the spring driven carriage, the return movement of the traveling paper carrier in one direction under motor actuating influence being transmitted to the carriage whereby the carriage is retracted by the travel of the carrier.

5. The combination with a writing machine including a reciprocatory carriage and a reciprocating paper supply carrier mounted independent of the machine for unison travel therewith, a pair of motive devices pertaining to the paper supply carrier for driving the paper supply carrier first in one direction and then in the other, one of said motive devices being opposed by the other device the latter device being intermittently engageable with the carrier and means for effecting such engagement at will of the operator.

6. The combination with a writing machine including a reciprocatory carriage and a reciprocatory paper supply carrier mounted independently of the writing machine for unison travel, motive means for advancing the carriage and paper supply carrier in one direction and motor actuating means intermittently engageable with the reciprocatory paper supply carrier independently of the writing machine carriage for returning the carriage and paper carrier in unison preparatory to succeeding line writing operations. 5
7. The combination with a traveling paper supply carrier for a writing machine, of motor actuating means therefor for directly driving the carrier first in one direction and then in the other independently of any actuating influence of any corresponding movement of parts of the writing machine. 10
8. The combination with a writing machine including line spacing means and a traveling paper supply carrier for the writing machine, auxiliary spring means for advancing the carrier in unison with the carriage of motor actuating means intermittently engageable with the carrier independently of the writing machine carriage and controlled by the operation of the line spacing means. 15
9. The combination with a writing machine including line spacing means and a traveling paper supply carrier for the writing machine, auxiliary spring means for advancing the carrier in unison with the carriage of motor actuating means associated with the carrier having intermittent operative engagement with the paper supply carrier independently of the writing machine carriage under control of the line spacing means to return the carrier after each line writing operation upon actuation of the line spacing 20 mechanism. 25
10. The combination with a writing machine operable through a step by step movement and a traveling paper supply carrier therefor, of motor actuating means for the carrier governed by the step by step movement of the writing machine, and means including an electric motor intermittently engageable with the paper supply carrier independently of the writing machine for effecting the automatic return movement of the writing machine and paper carrier in opposition to said first mentioned motor actuating means. 30
11. The combination with a traveling paper supply carrier for a writing machine, of an actuating motor therefor mounted for tilting motion into and out of operative driving relation with the carrier, means for tilting the motor into operative engagement in response to certain operations of the writing machine, and means for automatically disconnecting the motor by the motor propelled movement of the carrier. 35
12. A traveling paper supply carrier for a writing machine, an oscillatory propeller therefor movable into and out of actuating position by its oscillatory motion, means for manually oscillating the propeller into operative position, and means for automatically oscillating the propeller out of operative position upon predetermined travel movement of the carrier. 40
13. The combination with a writing machine including line spacing means and a traveling paper supply carrier therefor, of an oscillatory propeller movable into and out of operative position by its oscillatory motion, an operative connection between the line spacing means and propeller by which the operation of the line spacer means effects operative connection of the propeller, and means for automatically rendering the propeller inoperative upon predetermined travel movement of the carrier. 45
14. A traveling paper supply carrier for a writing machine, independent motive means for directly propelling the carrier alternately in opposite directions independently of the actuating influence of any corresponding movement of parts of the writing machine, and means for energizing one of said motive means by the operation of the other. 50
15. A traveling paper supply carrier for a writing machine, including a traction bar carried thereby, a rotary driver intermittently engageable with the traction bar, motive means for the driver, said traction bar and driver being relatively adjustable into and out of operative relation, and means for relatively adjusting the driver and traction bar into and out of operative relation at selected points in the path of the traveling carrier. 55
16. A traveling paper supply carrier for a writing machine, including a traction bar carried thereby, a rotary driver movably mounted for movement into engagement therewith, motive means for the driver and means for energizing the motive means to operate the rotary driver against the traction bar. 60
17. A traveling paper supply carrier for a writing machine including a gear rack, a driving pinion intermittently engageable with the gear rack, motive means for the driving pinion, and means for moving the gear pinion into and out of driving engagement with the carrier rack at the opposite limits of the path of travel of the carrier. 65
18. A traveling paper supply carrier for a writing machine including a gear rack, a driving pinion intermittently engageable with the gear rack, motive means for the driving pinion, and means for moving the gear pinion into and out of driving engagement with the carrier rack at selected points of the path of travel of the carrier. 70
19. A traveling paper supply carrier for a writing machine, a bar carried thereby, a wheel engageable therewith for actuating the carrier, motive means for the wheel, and means for relatively adjusting the bar and wheel into and out of driving relation. 75
20. The combination with a writing machine including a reciprocatory carriage and a traveling paper supply carrier therefor, of motive means for returning the paper carrier after each line writing operation, and an interconnection between the carrier and carriage through which the writing machine carriage is returned by the return of the paper carrier. 80
21. A traveling paper supply carrier for a writing machine, a reversible actuator therefor, motive means for the actuator and reversing means for effecting operation thereof, first in one direction and then in the other to correspondingly propel the carrier. 85
22. A writing machine including a line spacing means, a traveling paper supply carrier therefor, a reversible actuator for the carrier, motive means for the actuator, and means for reversing the operative direction of the actuator by operation of the line spacing means. 90
23. A writing machine including a line spacing means, a traveling paper supply carrier therefor, a reversible actuator for the carrier, motive means for the actuator, and means for reversing the operative direction of the actuator by operation of the motive means. 95

24. A writing machine including a line spacing means, a traveling paper supply carrier therefor, a reversible actuator for the carrier, motive means for the actuator, a movable clutch controlling the actuator, and means for shifting the clutch for effecting reversal of the driving operation thereof and thereby reversing the direction of movement of the carrier.
25. A writing machine including a line spacing means, a traveling paper supply carrier therefor, a reversible actuator for the carrier, motive means for the actuator, a movable clutch controlling the actuator, and means for shifting the clutch by the operation of the line spacing means for effecting reversal of the driving operation thereof and thereby reversing the direction of movement of the carrier.
26. A writing machine including a line spacing means, a traveling paper supply carrier therefor, a reversible actuator for the carrier, motive means for the actuator, and electro-magnetic means controlled manually for effecting reversal of the driving operation of the actuator and thereby reversing the direction of the movement of the carrier.
27. A writing machine including a line spacing means, a traveling paper supply carrier therefor, a reversible actuator for the carrier, motive means for the actuator, and electro-magnetic means controlled by the line spacing means for effecting reversal of the driving operation of the actuator and thereby reversing the direction of movement of the carrier.
28. The combination with a writing machine including line spacing means, and a travelling paper supply carrier for the writing machine, of motor actuating means pertaining to the carrier and motion transmitting means engageable in alternate positions for synchronizing the operation of the line spacing means with the travel of the carrier at either the beginning or end of its cycle of movement at the will of the operator.
29. The combination with a writing machine including line spacing means, and a traveling paper supply carrier for the writing machine, of motor actuating means for the carrier, and means for automatically actuating the line spacing means by the travel of the paper supply carrier as the latter reaches a predetermined point in its path of travel.
30. The combination with a writing machine including line spacing means, and a traveling paper supply carrier for the writing machine, of motor actuating means of the carrier, and means for automatically actuating the line spacing means by the retractive movement of the paper supply carrier.
31. The combination with a writing machine including line spacing means, and a travelling paper supply carrier for the writing machine, of motor actuating means pertaining to the paper supply carrier for actuating the paper supply carrier and operative means for actuating the line spacing means in timed relation with the movement of the paper supply carrier.
32. A traveling paper supply carrier for a writing machine, an oscillatory propeller therefor movable into and out of actuating position by its oscillatory motion, and means for oscillating the propeller into and out of actuating position to start and stop the travel of the carrier in one direction.
33. A unitary combination consisting of a paper carrier, a motor for moving it in one direction, another motor for moving it in another direction, and means for operatively connecting it to a moving typewriter carriage whereby the typewriter carriage limits the movement of the carrier in accordance with the amount of movement of the typewriter carriage in one direction and the carrier motivates the typewriter carriage in the other direction.
34. A unitary combination consisting of a paper carrier, a motor for moving it in one direction, another motor for moving it in another direction, and means for operatively connecting it to a moving typewriter carriage whereby the typewriter carriage limits the movement of the carrier in accordance with the amount of movement of the typewriter carriage in one direction to travel in unison with it, and the carrier motivates the typewriter carriage in the other direction.
35. A unitary combination consisting of a paper carrier, a motor for moving it in one direction, another motor for moving it in another direction, means for operatively connecting it to a movable typewriter carriage whereby the typewriter carriage limits the movement of the carrier in accordance with the amount of movement of the typewriter carriage in one direction to travel in unison with it, and the carrier motivates the typewriter carriage in the other direction, a support for the carrier, and means for mounting the carrier support upon a stationary part of a typewriter.
36. The combination with a writing machine including a stationary frame and a reciprocatory carriage of a paper supply carrier having a stationary support and a reciprocatory carriage, means for establishing a fixed relation between the typewriter frame and the carrier support to maintain the same stationary relative position with each other, means for operatively connecting the typewriter carriage and the paper carrier carriage to retain the same relative position to each other during their reciprocal movement, and actuating means adapted to operate the two carriages through motivating the paper carrier carriage, said actuating means including a spring motor actuating the carriage in one direction and an electric motor operatively connected to the paper supply carrier for actuating the carriage and carrier in the opposite direction.
37. A unitary device consisting of a support, a reciprocatory traveling paper carrier thereon, means for operatively connecting said carrier with a reciprocatory typewriter carriage, said carriage being spring driven in one direction, and a motor adapted to drive the carrier and there-through the typewriter carriage in the opposite direction.
38. The combination with a typewriter having a reciprocatory spring driven carriage, of an attachable device, consisting of a stationary support, a reciprocatory carrier mounted thereon, means for operatively connecting the carriage with the carrier, an electric motor for operating the carrier in opposition to the influence of said spring driven carriage, also mounted on said support and operatively connected to the carrier so as to operate the typewriter carriage.
39. A device for operating a spring driven typewriter carriage, consisting of an attachable unit comprising a support, a reciprocatory carrier mounted on said support, an electric motor for driving the carrier in a direction opposite to the influence of said spring driven carriage, and means for operatively connecting the carrier to

the typewriter carriage to operate the typewriter carriage in the same direction.

40. An attachable typewriter device, consisting of a support, an electric motor, a reciprocating carrier operatively connected with the motor, and means for operatively connecting the carrier with a reciprocating spring driven typewriter carriage for the purpose of operating the typewriter carriage in a direction opposite to the influence of the spring.

41. An attachable typewriter device, consisting of a support, an electric motor, a reciprocating carrier operatively connected with the motor, means for operatively connecting the carrier with a reciprocating spring driven typewriter carriage for the purpose of operating the typewriter carriage in a direction opposite to the influence of the spring driven carriage, and means for holding the support in proper relative position to the typewriter base.

20 42. The combination with a traveling paper supply carrier for a writing machine of an actuating motor therefor mounted for movement into and out of operative driving relation with the carrier, means for moving the motor into operative engagement in response to certain operations of the writing machine and means for automatically disconnecting the motor by the motor propelled movement of the carrier.

30 43. A detachable power unit for returning the reciprocating carriage of a writing machine normally driven in one direction by a spring motor, said power unit including a reciprocating bar mounted independently of the writing machine 35 and detachably connected to said reciprocating carriage through a pair of spaced parallel bars for travel movement therewith in a path parallel to the direction of travel thereof, a normally disconnected motor and means for intermittently 40 operatively connecting and disconnecting the motor with said bar for causing said motor to return said bar and said carriage against the force of said spring.

44. A detachable power unit for returning the 45 reciprocating carriage of a writing machine driven in one direction by a spring motor, said power unit including a reciprocating bar mounted independently of the writing machine and connected to said reciprocating carriage for unison travel therewith in a path parallel to the direction of travel thereof, a normally disconnected motor, manually controlled means for initiating the operative driving engagement of the motor and said bar for causing the motor to return the 55 carriage against the force of said spring and means operated by the power transmitted by the motor for disengaging the motor from said bar upon the return of the carriage.

45. A detachable power unit for returning the 60 reciprocating carriage of a writing machine driven in one direction by a spring motor, said power unit including a reciprocating bar mounted independently of the writing machine and detachably connected to said reciprocating carriage 65 for travel therewith in a path parallel to the direction of travel thereof, a motor movably mounted for bodily movement into and out of driving engagement with the bar to return said bar and said carriage against the force of said spring.

70 46. A detachable power unit for returning the reciprocating carriage of a writing machine driven in one direction by a spring motor, said power unit including a bar connected to said reciprocating carriage for unison travel therewith in a 75 path parallel to the direction of travel thereof, a

motor adjustably mounted for bodily movement into and out of engagement with said bar to return said bar and said carriage against the force of said spring and a portion carried by said bar for engagement with the motor to move the same out of engagement with said bar upon the return of said carriage.

5 47. A detachable paper carrier attachment for use with writing machines having a reciprocating carriage spring driven in one direction, said paper carrier including a pair of spaced arms frictionally engaging said carriage, and a motor for returning the carrier and through said arms said carriage against the force exerted by said spring at the will of the operator.

10 48. A detachable power unit for returning the reciprocating carriage of a typewriting machine actuated in one direction through a step by step movement, said power unit including a motor, a bar connected to said reciprocating carriage for travel therewith in a path parallel to the direction of travel thereof, the bar and motor being engageable and disengageable by the bodily movement of one of said members relative to the other for causing said motor to return said carriage against the force of said spring when engaged with said bar.

15 49. A detachably mounted power unit for operating reciprocating carriages, consisting of a support upon which are mounted a motor having 30 a rotary armature and a reciprocating carrier frictionally connectible thereto, means for operatively connecting the carrier to a reciprocating device for transmission of movement thereto and means for holding said support in a detachably 35 mounted position relative to the reciprocating device.

50. An attachment for a typewriter having a reciprocating carriage spring driven in one direction, including a bar mounted independently of 40 the typewriter for reciprocating movement in a direction parallel to the path of movement of the reciprocating carriage, means for detachably connecting the reciprocating bar to the typewriter carriage, for unison movement therewith, an 45 actuating motor associated with said bar, one of said members being bodily movable into and out of operative engagement with the other for driving said carriage in a direction opposite to the force exerted by said spring upon said carriage.

55 51. An attachment for a typewriter having a reciprocating carriage spring driven in one direction including a bar mounted for reciprocating movement in a direction parallel to the path of travel of said carriage, means for detachably connecting said bar to said carriage including a pair of bars engaging opposite ends of the carriage, and a motor mounted for movement towards the bar for driving the same and the carriage in opposition to the force exerted by said 60 spring to return the carriage through said bar.

52. An attachment for a typewriter having a reciprocating carriage spring driven in one direction including a bar mounted for reciprocating movement in a direction parallel to the path of 65 travel of said carriage, means for detachably connecting said bar to said carriage including a pair of bars engaging opposite ends of the carriage, a tiltably mounted motor for actuating the bar when tilted in contact therewith to return the 70 carriage in opposition to the force exerted by said spring.

53. An attachment for a typewriter having a reciprocating carriage spring driven in one direction including a bar mounted for reciprocating movement in a direction parallel to the path of 75

- travel of said carriage, means for detachably connecting said bar to said carriage including a pair of bars frictionally engaging opposite ends of the carriage, a movably mounted motor for adjustment into engagement with the bar to actuate the bar and carriage in opposition to the force of the spring and means for ejecting the motor out of engagement with the bar at the end of the return movement of the carriage.
- 10 54. An attachment for a typewriter having a reciprocating carriage mounted for to and fro movement, said attachment including a bar mounted for reciprocating movement in a direction parallel to the path of travel of the carriage, detachable means for interconnecting the bar to the carriage, a motor associated with said reciprocating bar, one of said members being bodily movable relative to the other into and out of engaging relation for effecting movement of the typewriter carriage under influence of the motor and means for automatically moving one of said members relative to the other to disengage
- 15
- 20

the motor from driving relation as the typewriter carriage approaches the limit of its travel.

55. The combination with a writing machine including line spacing mechanism, and a travelling paper supply carrier therefor, of motor actuating means pertaining to the paper supply carrier for transmitting travel motion thereto, and an operative connection between the line spacing mechanism of the writing machine and the motor actuating means of the paper supply carrier for initiating the movement of the paper supply carrier by operation of the line spacing mechanism.

10 56. The combination with a writing machine including line spacing mechanism, and a travelling paper supply carrier therefor, of motor actuating means pertaining to the paper supply carrier for transmitting travel motion thereto, and motion transmitting means for actuating the line spacing mechanism of the writing machine, 20 by the movement of the paper supply carrier.

JOHN Q. SHERMAN.

CERTIFICATE OF CORRECTION.

Patent No. 2,092,029.

September 7, 1937.

JOHN Q. SHERMAN.

It is hereby certified that error appears in the printed specification of the above numbered patent requiring correction as follows: Page 6, first column, line 54, claim 30, for the word "of" read for; and that the said Letters Patent should be read with this correction therein that the same may conform to the record of the case in the Patent Office.

Signed and sealed this 16th day of November, A. D. 1937.

Acting Commissioner of Patents.

- travel of said carriage, means for detachably connecting said bar to said carriage including a pair of bars frictionally engaging opposite ends of the carriage, a movably mounted motor for adjustment into engagement with the bar to actuate the bar and carriage in opposition to the force of the spring and means for ejecting the motor out of engagement with the bar at the end of the return movement of the carriage.
- 10 54. An attachment for a typewriter having a reciprocating carriage mounted for to and fro movement, said attachment including a bar mounted for reciprocating movement in a direction parallel to the path of travel of the carriage, detachable means for interconnecting the bar to the carriage, a motor associated with said reciprocating bar, one of said members being bodily movable relative to the other into and out of engaging relation for effecting movement of the typewriter carriage under influence of the motor and means for automatically moving one of said members relative to the other to disengage
